UNITED STATES PATENT OFFICE.

WILLIAM GADKE, OF PHILADELPHIA, PENNSYLVANIA.

TERMINAL FOR CONDUCTORS.

1,247,656.

Specification of Letters Patent. Patented Nov. 27, 1917.

Application filed January 22, 1916. Serial No. 73,685.

To all whom it may concern:

Be it known that I, WILLIAM GADKE, a citizen of the United States, residing in Philadelphia, Pennsylvania, have invented 5

5 Terminals for Conductors, of which the following is a specification.

One object of my invention is to provide a relatively simple, easily applied terminal particularly designed for use with 10

insulated conductors, the construction being such that the terminal will be mechanically as well as electrically connected to the conductor so that it cannot easily be detached.

15 It is further desired to provide a terminal which may be caused to make a satisfactory electrical connection with a stranded conductor without the necessity for soldering or sweating it thereto, the invention being 20

particularly adapted for use with conductors having a relatively heavy solid insulating covering such as rubber or gutta-percha, although being by no means confined to use solely with the same.

25 These objects and other advantageous ends I secure as hereinafter set forth, reference being had to the accompanying drawings, in which,

Figure 1 is a detached perspective of a 30 terminal constructed according to my invention;

Fig. 2 is a vertical longitudinal section of the terminal shown in Fig. 1, illustrating it as applied to an insulated conductor;

35 Fig. 3 is a detached elevation, partly in section, illustrating a conductor with my terminal mounted thereon and showing the device with which it is designed to coat.

In the above drawings 1 represents an 40 electric conductor formed of a number of twisted wire strands usually of copper. This conductor has a covering 2 of rubber, gutta-percha, or other insulation such as is usually considered necessary for the safe

45 distribution of electric currents of high tension. To provide a terminal for this conductor I employ a cylindrical metal structure in the form of a sleeve 3 having in one end a relatively large cylindrical cavity or 50 recess designed to be comparatively closely fitted by the insulating material 2 of the conductor. In the opposite end of this terminal structure is a smaller and shallower recess 4 connecting with the larger cavity

through a central passage of suitable diameter to more or less closely fit the conductor 1. 55

In applying the terminal to a conductor or cable, the insulation is removed from a suitable length of the same and the bare conductor is passed into the large recess of 60 said terminal through the passage of reduced diameter in the partition between the recesses so that the end of the insulation 2 closely fits against the bottom of said recess. The extremity of the conductor is then upset 65 or opened out in the cavity or recess 4 so that its strands practically fill the same, forming a head composed of the laterally bent and more or less tangled mass of wire, the length of wire extended through the passage in the partition being determined by 70 experiment in order that it shall practically fill said recess 4. Thereafter, even if considerable tension be exerted on the conductor, it cannot be drawn out of the terminal 75 3, since the relatively sharp bends in the individual wire strands prevent the head 5 formed by the wires in the recess 4 from becoming sufficiently straightened or changed in shape to allow its constituent wires to 80 draw out through the comparatively narrow passage 6.

In order to detachably connect the terminal 3 with another conductor 7, for example, the latter may be provided with a receptacle 85 in the form of a cylindrical sleeve 8 whose hollow or cavity 9 is of such diameter as to be closely fitted by the terminal 3. This latter has a pressed out lug or projection 10 formed adjacent its rear end and is provided 90 with any suitable number of longitudinally extending slots 11 opening into its larger cavity so as to permit of its rear portion being sufficiently compressed or contracted in diameter to allow the projection after passing 95 into the hollow of the member 8 to spring into an annular recess 12 formed in the wall thereof. In Fig. 3 I have shown the member 8 as provided with a heavy insulating case or cover 13 but this may be 100 omitted without departing from my invention, the conductor being free to turn within the part 3 with which it makes good electrical contact.

I claim:—

105 The combination of a receptacle including a hollow metal sleeve having an interior annular recess and an interior substantially

central projection; a terminal in the form of a contractile metal sleeve fitting said recess and provided with a projection formed to fit the annular recess, said sleeve having a perforated partition dividing its interior hollow into two cavities; a conductor extending through one of the two cavities into the pas-

sage of the partition and laterally spread in the second cavity to form a head positioned to be engaged by the central projection of 10 the sleeve; with a body of insulation surrounding the conductor and extending into the first cavity of the terminal.

WILLIAM GADKE.
